TIMER FOR TRAFFIC SYSTEMS

Carl A. Glock, Los Angeles, Calif., assignor to
 Aeme Traffic Signal Company, Los Angeles,
 Calif., a corporation of California

Application April 24, 1939, Serial No. 357,697

4 Claims. (Cl. 172—239)

This invention relates to a timer for a traffic signal system.

An object of the present invention is to provide a timer suitable for use in a street traffic system which timer drum is provided with contacts connected with speed control devices so arranged that the timer drum may be driven at different speeds, each of which may be varied independently of each of the other intervals of the timer's motion. By a timer drum of this class, the times during which different streets are held open for traffic may be regulated independently of the times that other streets are held open and moreover, the timer allotted to clearance intervals may be regulated independently. These regulations may be effected by the apparatus of the present invention automatically or by local manual control or by a remote central controlling station which is intended to control a plurality of different timers located in different portions of the city.

It is a further object of the present invention to so construct the timer drum and provide the drum with necessary contacts and devices, that on one timer drum is located means for energizing semaphores, means for energizing red and green lights, means for energizing bells, all correlated and properly positioned on the same timer drum which possesses contacts by which the motion of the timer drum may be regulated through the timer drum itself.

It is a further object of the present invention to provide a switching mechanism connected with the timer drum by which the drum may be set so that either only semaphores are operated at the intersections or only green and red lights are operated at intersections, or both semaphores and the lights may be operated at intersections, or a warning signal or flasher only operates.

It is a further object of the present invention to provide a timer including a switching drum which can be moved alternately to two positions to manually regulate the motion of the timer drum and thereby the display of any one or all of such traffic signals, and which can be moved to another position in which the motion of the timer drum will be automatically maintained, and which is movable to a further position in which the motion of the timer drum may be regulated from a remote control station and movable into a still further position in which a plurality of timers may be automatically regulated from the timers themselves, but in which different timers will be coordinated or synchronized along a street.

Various further objects and advantages of the present invention will be apparent from the description of a preferred form of timer embodying the invention. For this purpose there is hereinafter described a preferred form or example of a timer embodying the invention. The description is given in connection with the accompanying drawing, in which

The single figure of the accompanying drawing is an electrical diagram of the circuits for the local timers and switches for controlling the same, with the timer drum and switch drums developed to show the contacts and with the contact fingers placed at the sides of their respective drums to facilitate tracing the circuit.

The apparatus as illustrated in the drawing comprises a timer drum and two switches S1 and S2 to be used in connection therewith for connecting the timer drum to this signal apparatus at street intersections. Any suitable or preferred construction of signal apparatus may be employed for use with the timer. Such signal apparatus preferably comprises a semaphore arm, a red and green light, and a bell. This signal apparatus is connected to the apparatus illustrated in the drawing, as follows:

Finger F20 is connected with a line leading to an apparatus (not shown) for folding the signals. Finger F22 is connected with a line leading to a motor (not shown) for moving the semaphore arms. Finger F24 is connected by a line LT, the purpose of which is hereinafter pointed out. Finger F10 connects with a current supply line. Finger F13 connects with line SP, the purpose of which is hereinafter pointed out. Finger F15 connects with line R1, the purpose of which is hereinafter pointed out.

The lines connecting the timers with the signal heads connect with the timer as follows:

Contact fingers F41, F42, F43, F49, F50 and F53, respectively, connect with lines FN1, AM, FN2, GN, RN and B, which lines lead to signal heads H1, H3, while the lines FE1, AE, FE2, GE, RE and B which connect with signal heads H2 and H4 connect with timer fingers F45, F46, F47, F51 and F52 and F53, respectively. Lines FL which connect with all of the timer heads are shown connected into the timer as follows:

Line FL connects with finger F31 and line FO connects with finger F21.

The timer includes a drum of which D is a development, said drum surface is normally driven to the right as indicated in the figure, and is provided with a plurality of contacts. 1 110

and 2 respectively, indicate coils of a disc type electric motor, for example of the type employed in revolving records on a phonograph. Said motor drives the timer drum. Coils 1 and 2 are arranged to urge the disc of the motor in opposite directions and in the apparatus of this invention, coil 1 is usually continuously energized at constant potential during operation to drive the motor so that it constitutes a driving coil, while coil 2 is intermittently energized at a less or equal potential to vary the speed of rotation of the motor or stop the motor by applying a field for bucking the field generated by the coil 1, so that coil 2 may be considered as a bucking coil or retarding or braking element.

One side of each of the coils is indicated as grounded at 7 and the other sides of the coils are to be connected with positive potential by various switching elements of the apparatus, as hereafter described. 3 indicates a fixed resistor which is employed in certain operations of energizing the bucking coil 2, and 4 indicates a rheostat having a number of switch arms, which is also used in controlling the energy applied to the bucking coil 2.

The apparatus is also indicated as comprising a manually operated switch 5, the purpose of which is to fold the semaphore signals, a thermostat 6 to control the current supply to the flashers, and switch drums S1, S2 and S3.

The switch drums S1 and S2 are shown as separate drums for convenience, but may be one, or mounted upon a single shaft because they are intended to be positioned always in corresponding positions. These switches S1 and S2 are of the manually operated rotor type switches having contacts on drum surface 5, the developments of which are shown. The switch S3 is an independent rotor switch with contacts on its surface.

Now, first considering the switch drum S1. The switch drum S1 is shown as provided with the contacts C1, C1A, C2, C3, C4, C5 and C6, which contacts are intended to engage contact fingers F1 to F6 inclusive and F7 to F15 inclusive. In the construction of the switch, the fingers contact with the cams of the switch on only a line of contact and the contact fingers F1 to F6 are aligned on a line parallel to the axis of the cylinder of the switch drum surface S1. Also the contact fingers F7 to F15 are aligned in a line parallel to the other fingers. The two sets of contact fingers operating on the switch drum S1 are normally placed a distance apart on the drum surface, the distance between any two of the lines drawn through the drum surface which are separated by any one of the legends "Off", "Go", "Stop", "C", "A", or "R". They are indicated at opposite sides of the switch drum in order to clarify the description of the operation of the device.

In practice, the drum surface of the switch is intended to be operated to bring six different positions of the drum surface relative to the fingers. In the first of these positions, fingers F1 to F6 are on the line on the drum at the left of legend "Off", while fingers F7 to F15 are on the line to the right of legend "Off" and in the second position fingers F1 to F6 are on the line to the left of legend "Go" and the fingers F7 to F15 are on the line to the right of legend "Go", etc. The legends indicate the kind of operation to be effected by the apparatus when the switch drum is in respective position. The respective operations accomplished by these dif-

ferent positions will be more fully understood from the hereafter contained description of the operation of the apparatus.

Contact C1 is arranged to connect fingers F1, F2, F7 and F8 together whenever the drum of the switch is in either the "go", "stop", "C" or "A" position. Contact C1A connects fingers F1 and F7 when the switch S1 is in R position. Contact C2 connects fingers F3 and F9 when the switch S1 is in "off" position. Contact C3 is connected by a line with contact C1A so that in the R position, finger F10 is also connected with fingers F1 and F7. Contact C5 is an L-shaped contact which operates in the "go" position of the switch S1 to connect fingers F5 and F11 and F12. Contact C4 operates in the C position to connect fingers F4 and F11. Contact C6 operates in the "stop" position to connect fingers F6 and F14. Contact C6A connects fingers F12 and F13 in the R position and contact C6B connects fingers F14 and F15 in the R position.

The fingers F16 to F19 on switch S2 are aligned and the fingers F20 and F23 are aligned and these fingers are spaced apart on the drum the same distance as the fingers of drum S1. The drum S2 has the same six operating positions as the drum S1 and occupies the same relative positions at the same time. This may be accomplished by mounting the switch drum S2 on the same shaft as the drum S1 and the manual positioning of the switch drum may be accomplished by a knob or operating handle on the drum shaft or any other desired means. The surface S2 has contacts C7 to C10 inclusive and C10A, C10B and C10C. C10A, C10B, C10C operate only in the R position and at said position, the first of these contacts connects fingers F20, F21. The second connects fingers F22 and F23 and the third connects fingers F24 and F25. Contacts C7, C8 and C9 operate in all positions, except the "off" and R position to connect respectively fingers F16 and F21, F17 and F23, and F18 and F25. Contact C10 operates in the C and A positions to connect fingers F19 and F26.

The rotor switch S3 has a line of finger contacts F27 to F31 inclusive. There are provided four cams on the drum of switch S2, cams C11, C12, C13 and C14. There are four positions that this switch is intended to operate, a "flash" position, an "arm" position, and "arm and light" position and a "light" position. Legends are provided showing the line of contact of fingers F27 to F31 in these different positions. The word "Flash" appears at opposite ends of the drum surface since the opposite ends of development of the drum surface in practice constitute a single point.

In the "flash" position, contact C14 contacts fingers F30, F31. In the "arm" position contact C11 connects fingers F27, and F28. In the "arm and light" position contact C12 connects fingers F27, F28 and F29. In the "light" position contact C13 connects fingers F28 and F29.

There is provided a line of finger contacts F32 to F54 inclusive, operating upon the timer drum D. There are provided on this timer drum, contacts which make connections with different numbers of the fingers F32 to F54 inclusive, as the timer drum surface is revolved. In order to facilitate an understanding of the operation of the timer drum, dotted lines M, N, O, P are shown through the timer drum and the operations normally performed by the signal when the lines of contact are between any pair of these lines is indicated by the legends "North-South", "Stop", "180

"East-West" and "Stop". Thus, between lines M and N the "go" signals on the north and south streets are displayed, while "stop" signals are displayed on the east and west streets. When the fingers are between line O and P, the "go" signals are displayed on "east-west" streets and the "stop" signals displayed on "north-south" streets, and between the other intervals all streets display "stop" signs. The construction of the cams 10 on the timer drum will be understood from a description of the operation of the apparatus.

When the contact fingers F1 to F26 of the switches S1 and S2 are on the lines indicated as the "A" position, the switches S1 and S2 position 15 the apparatus for automatic operation without any coordination with the central station or remote control timer and without coordination with the timers for signals at other crossings on the same street.

20 In this position positive current supplied to main 10 is therefore imposed upon contact C1 and fingers F1, F7 and F8. The circuits thereby energized will be traced, referring only to the fingers, contacts and devices included in the lines 25 as the numbering of the lines tends only to confuse tracing of the circuits.

F7 being energized to positive potential, motor driving coil 1 is directly energized to ground 7 so that during all time the switch S1 is at the "A" 30 position, the motor coil 1 is energized at constant potential, thereby tending to drive the drum surface D. Finger F7 also connects with finger F36 operating on timer drum D, which continually contacts with contact C24 which is shown as electrically connected with contacts C20, C23, C21, 35 C25, C26, C27 and C28, C29 C30 and C31.

Contacts C25 and C26, C27 and C28 are aligned in position to contact with finger F37. These contacts are respectively disposed in alignment 40 with the lines M, N, O, P so that at the start of each of the four intervals of the intended operation of the signals, one of the contacts C25, C26, C27 or C28 for a short time energizes finger F37. Finger F37 is connected through resistor 3 to a 45 bucking coil 2, hence to ground 7. Accordingly, at the start of each interval of operation, the motor 1 is slowed down due to the action of the bucking coil 2 being energized through resistor 3.

The contacts C25, C26, C27 and C28 thereby 50 regulate, as later pointed out, the time at which the bells are rung and the time that the semaphore motors are energized. Contact C21 during most of the time that the fingers are traveling between lines M and N, contacts with finger 55 F38 supplying positive potential therefrom to rheostat 4 from whence a circuit may be traced to finger F26 on the switch drum S2 which is connected in the A position through contact C10 with finger F 19 which leads back to the buck- 60 ing coil 2, hence to ground 7. Accordingly, during most of the time that the fingers on the timer drum are passing from line N to the line M, the bucking coil 2 is energized to slow down the motor 1 and the speed of the motor 1 is 65 under control of the tap on rheostat 4 connected to finger F 38 so that this interval of operation may be lengthened or shortened throughout a wide range, as may be desired in operation of the signal. It should be noted in this connection 70 the action of the timer in slowing motor operation in this portion of the revolution of the timer, does not in any way affect the length of time that the motor will occupy in driving the drum through any of the other intervals of the timer. The contact C29 is for operation in

identically the same manner as contact C21, except that this contact operates in the east-west period or while the fingers are moving from line P to O. In said interval or in the major portion thereof, contact C29 energizes finger F39 80 to positive potential which leads to its tap on rheostat 4, and hence as before described, back to the bucking coil 2. The breaking action of the bucking coil 2 in the east-west period may therefore be regulated to obtain any desired 85 period of time quite independently of the period of time allotted to the north and south interval.

The contacts C30, C31 are brought into play during the different clearance or all stop intervals of the traffic signal and in those intervals or in part thereof, connect respectively with fingers F40 and F40A which lead to separate taps on the rheostat 4, so that the bucking coil 2 is energized from the rheostat 4, whenever contacts C30 or C31 are covered by either finger 90 F40 or F40A. The resulting effect is that depending upon the relative positions of the rheostat taps connected to fingers F40 and F40A, the length of the respective clearance intervals may 95 be regulated as desired and this regulation is 100 equally independent of the times allotted to the other intervals of the signals.

Contact F1 being energized to the positive through contact C1 on switch drum S1, energizes finger F54 which in turn energizes contacts C49, C50, C51, C52 and C53 of the timer drum. Contacts 50, 51, 52 and 53 are shown aligned and positioned at the lines M, N, O, P so that at each change of interval of the timer, there is a short energization of the contact 110 finger F53. Contact finger F53 through line B, connects with the bells of the signal heads which have their opposite sides grounded, as shown in Figure 3, whereby the bells are rung at the start of each change of interval. 115

The apparatus of the present invention provides a means by which the traffic signals may be regulated either by operating, respectively, green and red lights to indicate traffic movement and traffic stopping orders for the different 120 streets, or the signals may operate semaphores displaying, for example, legends "Go" and legends "Stop". Or, the signal may operate both the red and green lights and the semaphores. 125

The signal has a further position of operation where it merely flashes a red light as a warning and is not operating actually as a traffic regulator.

It is a particular advantage of the apparatus 130 of this invention that there is included a means operating from a common control for regulating the traffic movement and traffic stopping conditions selectively, either by lights or semaphores. The power required to move the semaphores is relatively small. Accordingly, in the day time, by operating the signal to actuate only the semaphore arms, a great saving of power 135 may be had. At night time, lights are necessary either as sole traffic indicating devices or at least illuminating the semaphores. Where lights are provided for operating in the day time as signalling elements as well as at night, much more powerful lights are required, consuming a larger amount of current than where 140 the lights are for operation only at night. Where 145 the signal includes lights intended for operation only at night, the lights may be of comparatively small power, using little electric energy.

The operation of the traffic signals in this 150

automatic position of switches S1 and S2 will first be described as it takes place with the switch S3 in the "light" position or in the position in which red and green lights or other 5 equivalents only are energized.

Contact finger F8 which is energized at positive potential through contact C1 with switch S1 at the "A" position, connects with finger F28 of switch S3 which connects through contact 10 C13 in the "light" position to finger F29 which connects with finger F18 through contact C9 of switch drum S2 to finger F25 hence to finger F42 on the timer drum.

Thus, in this position of operation finger F48 15 is continuously at positive potential. Finger F48 connects with contact C42 continuously during revolution of the timer drum and this contact C42 is continuously connected with contacts C43 to C48 inclusive, whereby in this condition of 20 operation of the apparatus, all of the latter contacts are continuously at positive potential.

Starting with the fingers considered as on the 25 drum surface on the line at the right of the drum surface and moving towards the left of the drum surface, in this position, which is in the center of one clearance interval of the timer, both fingers F50 and F52 are energized. As shown 30 in Figure 3, fingers F50 and F52, respectively, lead to red lights on north-south and east-west streets, so that red lights are displayed in both directions. Just before the line P is reached, fingers F52 falls off contact C44 and the red 35 lights east and west are extinguished. Finger F51 contacts with contact C47. When finger F51 is energized, the green east and west lights are energized, indicating that the east and west lane is open to travel. This condition of the lights continues until line O is reached when finger F51 drops off of C47, extinguishing the green lights.

40 Shortly thereafter C44 again contacts F52 to display red lights east and west. While the fingers are moving from O to N both streets have red lights displayed thereto. When the fingers reach line N, finger F50 falls off of contact C45 extinguishing the red lights on north-south streets and shortly thereafter, finger F49 contacts with 45 C43, energizing the green lights north and south.

Accordingly, while the fingers move from line N to line M, green lights are displayed north and south and red lights east and west. On reaching line M, finger F49 falls off of contact C43 extinguishing the green lights and shortly thereafter, fingers F50 again contacts with C45 illuminating the red lights north and south, so that 55 while the fingers pass from line M to line P red lights are displayed in all directions.

It is to be noted that the time that it takes the timer drum to pass through each of these different intervals is all independently regulated and controlled by contacts on the same timer drum so that the length of any one of these intervals may be brought to any desired value without lengthening or shortening, unless desired, any one of the other intervals.

60 The foregoing completes the description of the operation of the apparatus on the "A" position of switches S1 and S2 and "light" position of switches S3. If it is desired to energize the semaphore arms in place of the lights, the switch S3 is turned to bring in contacts C11 to close F27 to F28. In this position, the red and green lights 65 will not operate. In this position, however, F8 on switch S1 is energized to positive potential as before described, and connects with finger F28 through contacts C11 to finger F27, hence to

finger F17 on switch S2 through contacts C8 to finger F23 and hence to finger F44, so that in the arm position of the switch S3 and automatic or "A" position of switches S1 and S2, finger F44 is continuously maintained at positive potential. Finger F44 continuously contacts with contact C37 which is connected with contacts C33, C36, C38 and C40; whereby all of these contacts are continuously energized at positive potential.

Considering now the fingers moving across the 80 drum D from the right hand to the left hand, the first operation which occurs just before the P line is reached corresponding to just before the start of the "go" interval for east and west traffic.

Contact C39 moves across fingers F45 and F46, and shortly thereafter finger F47 contacts with C40. Positive potential is therefore placed on F47. As later pointed out in the description of the circuits for the semaphores and other signals at the crossing, fingers F45 and F47 leading to

90 opposite sides of the field of the motor driving the semaphore arms and F46 leads through the armature to a ground connection. This energizes through the circuits, the semaphore motor to display the semaphore "go" signals on the east and west signal and to move the "stop" semaphore to the concealed position. The drum continues to travel and the fingers drop off of the cams C40, C39 as it is not necessary to energize the motor continually during the "go" period, but only at

95 the start of the "go" period or for a period of time sufficient to permit the motor to properly rotate the arms into the proper display positions. The resistor 3 connected with contacts C25 and C28 inclusive regulates the time that the motor is

100 operated. The drum travels to bring contact C41 across fingers F46, F47 and C38 in contact with C45. This occurs at the end or just before the end of the east-west "go" interval. The positive current is now applied through F45. The motor is

105 energized in the opposite direction, causing the "go" arm to be pulled back out of the display position. During all of this period of operation, the north and south signals are displaying "stop" semaphores which are operated as later described.

110 Therefore, while the drum surface passes from the line O to the line N all of the semaphores are displaying "stop" faces. When the fingers reach the line N on the drum, finger F43 is brought to positive potential by contact with C36 and fingers

115 F41 and F42 are connected by contact C34. The two north-south heads H1 and H3 have their motor field connected across fingers F41 and F43 and line F42 connects through the armature to a ground connection. The fingers travel off of

120 the cams C36, C34, so that they are now displayed on north and south streets "go" semaphores and the east and west streets are still displaying "stop" semaphores. This condition continues until the line M is reached when contact

125 C33 brings finger 41 to positive potential and fingers F43 and F42 are connected by contact C35. The motors are reversely energized, the "go" semaphore moved to the concealed position and the "stop" semaphore moved to the display position.

130 Therefore, all signals on both north and south and east and west streets are displaying "stop" signs and on all "stop" or clearance is provided until the fingers reach the line P, whereupon the operations are repeated.

135 In the "arm and light" position of the switch S2, it will be noticed that both finger 27 and finger 29 are energized at positive potential whereupon both contacts C37 and C42 are continuously energized. This causes the operations of sema-

phones and the red and green lights to take place simultaneously, the operations being identical to the operation described separately when switch S3 was on the line position and switch S3 on the 5 arm position.

When switch S3 is moved over to the "flasher" position, the bells are energized by finger F1 and contact C49 at the start of each interval, but no other takes place. Finger F30 and finger F31 10 although connected together, have no connection with the positive line in the "A" position of switch S1 and hence, the flasher does not operate.

When switches S1 and S2 are moved to the 15 position "C" on timers T1 and T2 the timer signals and heads are coordinated or synchronized at the intersections at which timers T1 and T2 are located.

All of the connections are made in the "C" 20 position which are made in the "A" position and identical operations are effected with the additional effect which is brought about by the action of the contact C4 on the S1 switch. Contact C4 in the "C" position, connects fingers F4 and F11. Finger F11 is connected with finger 25 F35 which is at positive potential. F4 of timer T1 leads to a finger F4 on timer T2 and on each of the other timers on different street intersections which it is desired to coordinate with the timer T1.

When operating on the coordinate control position, if any timer revolves the fingers on its drum so that its finger F35 contacts with the contact C21 before the corresponding finger F35 or any of the other timers reach this position, the 35 motor driving that timer is automatically stopped and held stopped until the last timer has its finger moved into contact with its contact C21. Thus, once during each revolution of all of the timers connected in coordination, they are started off at 40 the same period in their cycle, with the result that their operations are caused to take place practically simultaneously. In order to understand the circuits for this operation, we still assume that the second timer on the street reaches the contact C21 before the first or upper timer T1, in such a case a circuit may be traced as follows:

Positive current is taken from upper finger F2 through contact C1 of switch S1 to finger F7, 50 hence to finger F36 and hence to contact C23. Since finger F35 has not reached contact C21 but is still on C23, finger F35 is at positive potential, rendering finger F11 on switch S1 at positive potential, which through the contact C4 energizes finger F4, which through the coordinate control line CO energizes the finger F4 on the switch S1 of the lower timer, which through contact C4 energizes the finger F11, of that switch which is connected with finger F35 on the lower timer and which finger F35 it is assumed is in contact with contact C21.

Hence, contact C21 is at positive potential, contact C15 energizes finger F32 at positive potential and current is applied through the bucking 65 or braking coil 2 to ground. The potential applied through this circuit on this coil is equal to that applied to the other coil 1 of the lower timer motor, hence this motor is brought to a stop and will remain at a stop until the finger F35 on the upper timer drops off the contact C23 and until each and every other timer on the street also drops its finger F35 off of this contact.

The switch S3 provides a means by which under 75 this coordinate control, semaphores only may

be operated or red and green lights only may be operated or both red and green lights and semaphores may be operated. Moreover, it will be observed that on some streets, semaphore arms may be operated and on other streets, only lights 80 may be operated, but they may be coordinated together.

The positions indicated at "stop" and "go" 85 positions on the switches S1 and S2 are for manual regulation of the time intervals that the respective streets are open for traffic. Considering first the operations taking place with the switch set on the "go" position. In this position all of the contacts made in the automatic position are made except that on the switch drum S2 the contact C10 does not connect fingers F19 and F26 so that the circuits to the bucking coil 2 otherwise closed through the rheostat 4, are open and contacts C30, C31, C21 and C29 do not operate to slow down the motor which drives the timer drum. In place, the timer drum is brought to a stop at approximately the end of each "go" period by circuits as traced as follows:

Finger F5 through contact C5 places potential on both fingers F11 and F12. Fingers F11 and F12 are respectively connected to fingers F35 and F34 on the timer drum. When finger F34 contacts with C19 or when finger F35 contacts with C21 on the timer drum, whichever event occurs first, positive current is placed on contact C15 to finger F33 and hence to the bucking coil 2 to ground 7. It will be observed that the potential placed on the bucking coil is in this case equal to that placed on the coil 1. The result 100 is that the motor is stopped. It will therefore be seen that whenever the switches S1 and S2 are set upon the "go" position, the timer drum is stopped on one of the "go" intervals, depending upon which contact C21 or C29 is first 105 brought in contact with fingers F34 or F35. These contacts are shown located close to the end of the "go" intervals of the timer so that immediately after the switches S1 and S2 are rotated from the "go" position, the timer can then 115 move to quickly change the signals to the next "stop" or clearance period. The "go" position on the switches S1 and S2 is intended to operate in connection with the "stop" positions. In the "stop" position of switches S1 and S2, the 120 return from rheostat 4 is likewise broken, so that the motor 1 drives the timer at maximum speed, except as timer is stopped by the following operations.

In the "stop" position, finger F6 on switch S1 130 is connected through cam C6 with finger F14 which connects with the finger F32 on the timer drum. This finger F32 is in position to contact with either contact C16 or C17, which contacts are located in the clearance intervals of 135 the timer or in the all stop periods.

Accordingly, when either of these contacts touch finger F32 after the switch has been thrown to the "stop" position, the next contact C16 or C17 which touches finger F32 will energize contact C15, finger F33 and bucking coil 2 of the timer motor. As before, the bucking coil 2 of the timer motor is energized at full positive potential, completely neutralizing the effect of coil 1 and the motor stops. The motor is held stopped 145 until it is manually started again by moving the switches S1 and S2 off the stop position. It will be seen that by throwing the switches S1 and S2 first to the "go" position and then to the "stop" position, the intervals may be changed 150

manually in the following way. Assuming that the timer is on the line at the right of the figure and the switches are thrown to the "stop" position, the timer will be held at this interval until it is moved off the "stop" position. By moving switches S1, S2 to the "go" position, the timer will operate to change the signals and will continue to move until the finger F35 hits contacts C21, where the motor will again stop and be held stopped at this "go" interval, until the switches are again manually changed. When the switch is manually thrown again to the "stop" position, the motor will drive the timer until finger F32 contacts with contact C17 and again the motor will stop and an all stop period will be created until a further manual shift of the switches is effected. By the switching of the timer to the "go" position, the timer will turn and move again until contact C19 touches finger F34, where it will again be stopped, this time at the end of the north and south "go" interval. The timer will stay in this position until the switch is again automatically changed to "stop" position, whereupon the timer will travel until the contact C16 engages the finger F32, where it again stops at an all stop or clearance interval.

It is understood that the other circuits traced for the purpose of ringing the bells, lighting the lights and operating the semaphore arms are effected in the manual operation in the same way and the same variety of characters of operations can be effected as is effected when the timer is working automatically, the only difference being that the time that the different signals are displayed is dependent now upon the wish of the party manually operating the signal, rather than upon the automatic timer.

The contact C18 might engage the finger F32 in operating the signal on the "stop" period and stop the signal on one of the "go" periods, if the switches S1 and S2 are thrown at the proper times to the "stop" position to effect this result, but this contact does not interfere with the practical manual operation of the switch, in the series of operating steps described. The contact C18 is located in alignment with contacts C16 and C17 for certain other purposes and not to operate in this phase of the operation of the apparatus.

It will be noted that contacts C25, C26, C27 and C28 are energized at both the "go" and "stop" positions of switches S1 and S2, so that they operate as before through resistor 3 to slow the timer motor in its travel over these contacts sufficiently to give the desired time of motion of the motors driving the semaphore arms.

When switches S1 and S2 are positioned in the "off" position, finger F7 is no longer energized so that the timer motor is not energized and the timer drum ceases to move. Finger F3 connects with contact C2 and finger F9 which leads to contact F30. If switch S3 is in any position except the "flasher" position, no operation is effected by the signal when switches S1 and S2 are in the "off" position. In the "flasher" position, finger F30 connects through contact C14 with finger F31 to energize through the thermostat 6 to line FL which leads to the automatic flashers provided on the heads to continually flash a red light. The purpose of this operation is to use the traffic signal as a danger signal when it is not operating for regulating traffic.

When switches S1 and S2 are positioned in the R position, the timer is intended to be operated by the remote control timer on central station,

This timer provides six lead wires to the switches S1 and S2, the purpose of which is to control the operation of the signals automatically from the distantly located central station and to change the intervals of traffic regulation automatically from the central station in accordance with the setup that may be imposed on the signals at that point. When a plurality of streets are provided with timers similar to the timer illustrated in the figure and similarly connected with the corresponding six wires from the central timer, all of the signals may be operated together from the central station.

Of the wires leading from the central station, one wire P is always energized at a positive potential and connects with finger F10. In the remote control position, finger F10 connects with contact C3 which is electrically connected with contact C1A on switch S1 which connects with finger F7 to apply continuously a potential to motor coil 1 so that the motor coil 1 continually urges the timer drum into motion. This connection will cause contacts C25, C26, C27 and C28 to energize the bucking coil 2 through resistor 3 as in the previous operations, whenever one of those contacts hits finger F37, so that even when operating under control from a remote control or central station, the timer adjusts the speed of the timer drum's travel at the start of each interval to correspond with that desired in operating the semaphore motors.

The other timer drum contacts energized by finger F36 have no effect because C10 in the remote control position, no longer connects fingers F19 and F26 and therefore rheostat 4 is not connected back to the bucking coil 2. Wire SP from the central station connects with finger F13, hence by contact C6A connects with finger F12 which leads to contact F34. Whenever energy is passed over line SP, in the remote control position of switches S1, S2, the timer motor will be stopped whenever contact C19 engages the finger F34 to complete a circuit through the bucking coil 2. A line R1 is provided from the central controlling station.

The line R1 connects with finger F15 which in the remote control position through contact C6B connects with finger F14 on the switch drum, which finger is connected with finger F32 on the timer drum so that whenever the said wire R1 is energized, the timer will be stopped on each of the contacts C16, C17 and C18, whenever one of these contacts engages finger F32, since a circuit is then completed through C15 and F33 to the bucking or braking coil 2.

In operation, therefore, from the central station by applying either by an automatic timing of a switch or by a manual controlled timing switch, current to lines SP and R1, the motion of the timer can be controlled. For example, considering first the fingers of the timer on the right hand position, the timer will be held with finger F32 or contact C16, provided energy is imposed on line R1 to finger F15. This will maintain the signals at all "stop" or clearance positions. When it is desired to terminate this interval, the current supplied to finger F14 may be interrupted in the central station and the motor will then drive the timer ahead. The current should be immediately reimposed on finger F15, in order to catch the timer drum again on contact C18 which will hold the timer at the end of the east and west "go" interval until it is again desired to permit the timer to change to the clearance interval. Then by opening the line R1 at the central station, the

timer motor will again drive the timer ahead and the line R1 to finger F15 may be again closed to stop the timer on contact C17 or at the clearance interval. When the desired clearance interval 5 has been created from the central station, the current through finger F15 may be broken, whereupon the motor will drive the timer until finger F34 contacts with C19.

The motor will again be stopped and a desired 10 "go" interval or north and south traffic may be provided until at the central station, the current supplied to line SP is broken, whereupon the timer will again travel until contact C16 again contacts with F13, the operations being continued as before. All of the control of the change of intervals 15 might be effected by breaking current at desired intervals over a single line, such as line F15, by positioning the contact C19 in alignment with contacts C16, C17 and C19 if desired, but in such 20 a case there would be no means provided at the central station for determining which interval of the signal was being operated and the times desired for the "go" intervals might be imposing 25 upon the stop intervals. It will be noted that by having the contact C19 engage a different wire than the other contacts, the signal can be definitely started in a desired position as follows:

The line R1 leading to finger 15 is open and current is supplied to line SP leading to finger 30 13, until it is certain that the motor driving the timer drum has had sufficient time to have brought contact C19 in engagement with finger F34. It will then be known at the central station that the 35 signals are positioned at the "go" interval north and south and further automatic control of the signals may be then effected through manually switching or otherwise properly interrupting and establishing the current supply to fingers F13 and F15.

40 Line "AM" leading from the timer to finger F22 on switch S2 is always energized at positive potential when it is desired to have the remote control of the signals from the central stations actuate the semaphore of the signals. In this case, positive potential is placed from finger F22 to contact 45 C10B, hence to finger F23 to finger F44, energizing the contact C37 on timer drum, which actuates the semaphore motor during the different motions of the timer drum D precisely as described in connection with the motion of the drum 50 when the switches S1 and S2 are on the "A" or "C" positions, except that the time between changes in position of the semaphore arms is now varied and effected by the remote control rather 55 than by motion of the local timing contacts.

Line LT leading from central stations is always energized at positive potential when it is desired to operate the red and green lights of the signal. In such a case, finger F24 through contact C10C 60 energizes finger F25 and hence finger F48 and contacts C42 and connected contacts on the timer drum D. The green and red lights are therefore lit and extinguished during the revolution of the timer drum D in the same sequences of operations 65 as described when the timer drum is revolving under control of the local timer. It will be observed that either the lights or the semaphores separately may be used when the signals are working from the remote control station, or both the 70 semaphores and arms may be used together. It will also be observed that the bells are operated to each change of interval, since positive current is applied from finger F10 through contact C3 to contact C1A to finger F1 and hence to finger F54 75 and contacts C49, C50, C51, C52 and C53 to finger

F53 and to the line B leading to the bells of the signals.

The further line FO leading from the central station control is for the purpose of automatically folding up the arms of the signal when it is desired to shut down the signals, and to shut down central stations. In this case, positive potential is applied to the line FO and hence by way of finger F20 on switch S2 to contact C10A to finger F21 and hence to line FO leading to the folding magnets of the heads. 80

A switch 5 is located in the local timer for connecting finger F16 to F17 so that positive current may be applied in any of the "go", "stop", "C" or "A" positions of the switches S1 to fold the semaphores both downwardly when it is desired to shut down the signal. The circuit for this operation may be traced as follows: 85

Positive current is taken from finger F2 to contact C1 on switch 1, hence to finger F8 to finger F28 on switch S3. When switch S3 is either in the "arm" or "arm and light" position, positive current is imposed on finger F27, hence to switch 5 and finger F16, through contact C7 on switch S2, to a finger F21 which is connected 90 with the wire FO which leads to the signal head folding magnets. 95

While the particular form of the invention herein described is well adapted to carry out the objects of the present invention, it is understood 105 that various modifications and changes may be made without departing from the principles of the invention, and the invention includes all such changes and modifications as come within the scope of the appended claims. 110

I claim:

1. A timer comprising a contact drum, motor means for driving the drum, said motor means including a coil for normally driving the motor, and a retarding coil which, when energized, retards the motion of the motor, contacts for the drum positioned to be closed during different intervals of the motion of the drum, and a rheostat connected with said retarding coil and said contacts to effect different speeds of the motor 115 during different increments of the cycle of the drum. 120

2. A timer comprising a contact drum, motor means for driving the drum, said motor means including a coil for normally driving the motor, 125 and a retarding coil which, when energized, retards the motion of the motor, contacts for the drum positioned to be closed during different intervals of the motion of the drum, and a rheostat connected with said retarding coil and said contacts to effect different speeds of the motor 130 during different increments of the cycle of the drum, and contact means on said drum connected with said rheostat operated to reduce the speed of the drum a predetermined amount at 135 the start of each of its different intended increments of motion.

3. A timer comprising a contact drum, motor means for driving the drum, said motor including a winding for normally driving the drum 140 and an opposed winding which, when energized, retards the motion of the drum, rheostatic speed control means connected with said retarding winding, contacts on the drum connected with said rheostat, said rheostat including separate 145 adjustment means connected with individual contacts on the drum and capable of progressive adjustment to progressively and independently adjust the speed of the motor when each individual contact of the drum is engaged. 150

4. A timer comprising a contact drum, an electric motor for driving the drum including a driving coil and a retarding coil, a plurality of control means connected with said retarding coil, 5 and contacts on said drum connected with said control means for energizing said retarding coil at various desired potentials during different por-

tions of the cycle of the drum whereby different portions of increments of the drum's motion may take place at different speeds, and whereby said speeds are regulatable independently of each other.
